UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 14,586, dated January 29, 1881.

Application filed November 19, 1880. Term of patent 3½ years.

To all whom it may concern:

Be it known that I, CATHERINE O'HARA, of the city, county, and State of New York, have invented and produced a new and original Design for a Pattern of a Child's Costume, (numbered 8,980;) and I do hereby declare that the engraved prints accompanying this specification convey to any one accustomed to using paper patterns a clear understanding of how a garment made up by the pattern will appear.

The design shows a short skirt, a full shirred vest, the vest falling in a deep ruffle upon the skirt; and a jacket that displays narrow loose

fronts, buttoning upon the sides of the vest; a half-fitted back; a deep collar extending in 15 lapels to the top of the closing at the sides, and coat sleeves.

What I claim as my invention, and desire to secure by Letters Patent, is—

The design for a child's costume, as shown 20 in the engraved prints accompanying this specification.

CATHERINE O'HARA.
